CLAIM

The ornamental design for an exercise glove, as shown and described.

DESCRIPTION

FIG. 3 is a front view of a left-hand exercise glove according to the first and second embodiment of the present invention; and,

FIG. 4 is a front view of a right-hand exercise glove according to the first and second embodiment of the present invention.

The broken lines showing a thumb tip and fingertips in the figures illustrate environmental structure and form no part of the claimed design. All other broken lines show portions of the exercise glove and form no part of the claimed design.

1 Claim, 4 Drawing Sheets
